CLAIM

We claim the ornamental design for a light fixture, as shown and described.

DESCRIPTION

FIG. 1 is a perspective view of a light fixture;
FIG. 2 is a side view of the light fixture of FIG. 1;
FIG. 3 is a view of the opposite side of the light fixture shown in FIG. 2;

FIG. 4 is a front view of the light fixture of FIG. 1;
FIG. 5 is a rear view of the light fixture of FIG. 1;
FIG. 6 is a top view of the light fixture of FIG. 1; and,
FIG. 7 is a bottom view of the light fixture of FIG. 1.
The features shown in broken lines depict environmental subject matter only and form no part of the claimed design.
